Primary Examiner — George D Kirschbaum*Assistant Examiner* — Jennifer Watkins(74) *Attorney, Agent, or Firm* — Erickson Kernell IP, LLC(57) **CLAIM**

The ornamental design for a wrist brace, as shown and described.

DESCRIPTION

FIG. 1 is a front perspective view showing the brace secured on the wrist of a user;

FIG. 2 is front view of the brace of FIG. 1;

FIG. 3 is a rear or back view of the brace of FIG. 1;

FIG. 4 is a left side view of the brace of FIG. 1;

FIG. 5 is a right side view of the brace of FIG. 1;

FIG. 6 is a top view of the brace of FIG. 1;

FIG. 7 is a bottom view of the brace of FIG. 1;

FIG. 8 is a top perspective view of the brace of FIG. 1, showing the straps in an unsecured position; and,

FIG. 9 is a rear perspective view of the brace of FIG. 1, also showing the straps in an unsecured position.

The broken lines in FIG. 1 are for the purpose of illustrating environmental structure and form no part of the claim. The broken lines on the wrist brace are for the purpose of illustrating stitching that forms no part of the claim.

1 Claim, 6 Drawing Sheets---
